ELECTRIC SHAVING DEVICE

Filed Oct. 1, 1936

UNITED STATES PATENT OFFICE

2,216,673

ELECTRIC SHAVING DEVICE

Philip K. McGall, Newark, N. J., assignor to Art Metal Works, Inc., Newark, N. J., a corporation of New Jersey

Application October 1, 1936, Serial No. 103,571

5 Claims. (Cl. 30—43)

The invention relates to shaving devices and has as an object the provision of a device of this character wherein the movable member is resiliently held to its work.

5 It is a further object of the invention to provide a device of this character having novel means for the clearing out of severed hairs.

It is a further object of the invention to provide a device of the character referred to embodying improvements in details.

10 Further objects of the invention will appear from the following description when read in connection with the accompanying drawing showing an illustrative embodiment of the invention, and wherein:

Figure 1 is a side elevation;

Fig. 2 is an end view as seen from the left of Figure 1;

Fig. 3 is a detail central vertical section on line 3—3 of Fig. 2 drawn on a larger scale;

20 Fig. 4 is a vertical transverse section on line 4—4 of Figure 3; and

Fig. 5 is a detail transverse section of a cutter bar on an enlarged scale.

25 As shown the device comprises a handle 10 enclosing an electric motor 11 provided with a plug socket 12 and designed to operate the cutting device through the shaft 13 of the motor through the medium of universal joint means 14. 30 The universal joint means is necessary because of the angle at which the cutter casing 15 is placed with respect to the handle 10.

The casing 15 is formed with a cylindrical bore 16 in which revolves a rotor 17, which rotor is 35 formed with a helical rib 18 presenting a helical cutting edge. The casing 15 is shown as formed with a plurality of slits 19 defining a plurality of cutter bars 20, each cutter bar presenting at one side a cutting edge at the inner surface of the bore.

40 The skin-contacting surfaces of the cutter bars are desirably formed upon a curved surface as indicated in Figure 5 to allow the skin to protrude slightly between the bars in a manner well known in the art in order to secure a closer shave.

45 Dimensions for the device which are found to be satisfactory are a diameter of substantially three-sixteenths of an inch for the outer edges of the helix and with a pitch of the helix of substantially thirty turns per inch. With these dimensions and this pitch, the angle of the helical cutting edge to the axis of the rotor is substantially 3.25 degrees. It is found that if the 50 slits separating the cutter bars 21 are at right

angles to the axis, the resulting angles of the helical turns to the cutting edges carried by the bars of substantially 3.25 degrees will tend to cause the hairs to be dragged laterally before they are severed, resulting in a pulling on the beard. On the other hand, if the angle between the helical cutting edge and the edges carried by the bars is too small, the hairs will tend to be rolled along.

55 It is therefore preferred as shown to form the slits 19 separating the cutter bars at an angle to the axis of the rotor and it has been found by experiment that with the rotor formed as described, this angle of the slits to the axis should be about 2.50 degrees, thus providing an angle 18 between the relatively moving cutting edges of substantially .75 of a degree. This angle is found to be somewhat critical and it is at present preferred to make this angle not substantially more than one degree or less than about .50 of a degree. The operative part of the helix 18 is made slightly smaller in diameter than at its ends, in order that non-operative portions 21, 22 of the helix may contact the casing while the operative parts of the helix are preserved slightly 25 out of contact with the cutter bars, being spaced less than the diameter of a hair therefrom.

30 To hold the rotor 17 to its work, there is shown a presser bar 23 carried in a recess 24 in the casing 15 and resiliently pressed against the rotor 30 as by a compression spring 24'. The casing 15 is shown as retained in the extension 25 of the handle by means of a screw 26.

35 The casing 15 may be readily removed from the handle extension when freed by removal of screw 26 when the rotor may be slipped out of the bore. To prevent the presser bar being forced down into the bore upon the removal of the rotor, the recess 24 is desirably formed in the shape of a T as shown, the presser bar being 40 of a like configuration whereby the shoulders upon the presser bar may engage the complementary shoulders of the recess to support the bar. The presser bar also may be slid out of the recess whether the rotor is removed or not.

45 The extension 25 is shown as removably mounted in the handle, being retained in recess 27 in its end by means of a set screw 28 and located by a pin 29 projecting from the handle portion 10 into a hole 30 in the said extension 25.

50 To allow for escape of hairs severed by the rotor, the casing is shown as provided with a plurality of windows 31 upon each side of the casing adjacent the upper turns of the helix 18. As the helix 18 revolves a current of air will be produced 55

into one of the windows 31 and out of the opposite window upon the other side of the casing, thereby effectually ejecting the severed hairs.

The action of the presser bar 23 provides that in case of wear causing more than the necessary running clearance of the rotor, the contact of the end portions of the helix at the points 21, 22 will be maintained and therefore the clearance between the coacting cutting edges will always be the same, and in addition, any chattering will be eliminated to provide a quiet running device.

Minor changes may be made in the physical embodiment of the invention without departing from the spirit thereof within the scope of the appended claims.

I claim:

1. A shaving device comprising, in combination: a rotor comprising a solid core and a helical cutting edge carried by said core; a casing having a bore enclosing said rotor; transverse cutter bars carried by said casing at one portion of said bore and spaced longitudinally thereof; a cutting edge carried by each bar to coact with said helical cutting edge; means to drive said rotor; said casing having an opening in its side wall above said bars for escape of severed hairs.

2. A shaving device comprising, in combination: a casing having a bore; a series of transverse cutter bars carried by said casing at one portion of said bore and spaced longitudinally thereof; a cutting edge carried by each of certain of said bars; a rotor revolvable in said bore; a helix presenting a helical cutting edge carried by said rotor; said helix contacting with the wall of said bore at each end of said helical cutting edge and the latter revolving out of actual contact with said bars; a presser bar engaging said rotor at its ends and diametrically opposite said cutter bars; resilient means acting through said

presser bar to press the ends of the rotor into contact with said wall of the bore; and means to drive the rotor.

3. A shaving device comprising, in combination: a casing comprising a longitudinal bore and a longitudinal passage substantially coextensive with said bore, having a narrow portion opening into said bore and a wider portion remote therefrom; a series of cutter bars carried by said casing presenting cutting edges at a portion of said bore diametrically opposite said passage; a movable member operable in said bore; cutting edges carried by said member in coacting relation with said first named cutting edges; a presser bar having portions complementary to the portions of said passage, seated therein and contacting said member; spring means pressing said bar against said member; and means to cause relative movement between said cutting edges.

4. A shaving device comprising, in combination: a casing having a cylindrical bore; transverse cutter bars carried by one portion of the bore and spaced longitudinally thereof; a rotor mounted in said bore; a helical rib carried by said rotor; at least one turn of the rib at each end of the rotor exceeding in diameter the intermediate turns thereof; a presser bar contacting said excess diameter turns; and a spring to act through said bar to urge the rotor toward the cutter bars.

5. A rotor for use in a shaving device comprising: a helical member presenting a helical cutting edge; at least one turn of the helix at the respective ends thereof exceeding in diameter the intermediate turns thereof whereby to preserve the said intermediate turns from contact with cooperative portions of a shaving mechanism.

PHILIP K. McGALL.
